UNITED STATES PATENT OFFICE.

GEORGE H. BENJAMIN, OF NEW YORK, N. Y.

PIPE-CO尤PLING.

SPECIFICATION forming part of Letters Patent No. 376,061, dated January 10, 1888.

Application filed May 13, 1887. Serial No. 238,021. (No model.)

To all whom it may concern:

Be it known that I, GEORGE H. BENJAMIN, of the city, county, and State of New York, have invented certain new and useful Im- 5 provements in Pipe-Couplings, of which the following is a specification.

My invention relates to pipe-couplings of the class in which the two parts or half-couplings are identical in construction and adapted 10 to be automatically separable when submitted to any strains other than those due to the ordinary exigencies of use.

My invention further relates to and has for its object an automatically-separable coupling, 15 adapted to transmit air, steam, gases, or other bodies, hot or cold, and to utilize the pressure of such bodies within the coupling to pack and make a tight joint between the two parts of the coupling.

20 In the accompanying drawings, which illustrate my invention, similar letters of reference indicate like parts.

Figure 1 is a side elevation of my improved coupling. Fig. 2 is a longitudinal section. 25 Fig. 3 is a transverse section on the line 3 3 of Fig. 2. Fig. 4 is a transverse section on the line 4 4 of Fig. 2. Fig. 5 is a top view. Fig. 6 is an end view showing the end of the hooked latch engaging with the sleeve, and Figs. 7 30 and 8 are respectively a plan and section of one of the packing-rings.

Referring to the drawings, A indicates the body of a half-coupling made from metal, and either wrought or cast, as desired, and provided with an enlarged end or flange, B, into which is screwed a head, C. The face or abutting end D of the half-coupling is plain, and adjacent to the face and on the interior of the half-coupling is the seat E, shaped as the frustum of a cone. Within the half-coupling, and resting upon the seat E, are the annular conical packing-rings F G. The rings F G are divided from their periphery to their central port-openings, H, Figs. 7 and 8—that is 45 to say, a portion, I, of the body of the rings is removed, so as to allow the rings to contract their diameter, and so move along the packing-seat E when influenced by the pressure of the body transmitted through the coupling. When the rings are placed on the packing-seat, the openings or divisions I of the

rings F G are so located as not to come together. In other words, "to break joints."

Interposed between and bearing on the vertical portion of the flange B and ring G are the helical springs J. The springs serve to hold the rings F G in place when the half-couplings are separated, or when no body is transmitted through the coupling, and hence no pressure exerted upon the rings. The 55 spring or springs J are, however, unessential, and may be dispensed with.

On one side of the body of the half-coupling, and riveted thereto or formed integrally therewith, is the stud K, provided with inclined faces L M. Arranged on the opposite side of the half-coupling is a double stud, N, which forms a bearing for and on which is pivoted a hooked latch, O. One end of the latch is bifurcated to form the hooks P Q, Fig. 6, 70 and is likewise provided with the depending portion or tongue R, located between the hooks P Q. The other end of the latch has the handle S.

75 l is a bent spring, which bears at one end upon the body of the half-coupling and at the other end upon the under side of the handle, thereby serving to elevate the handle and depress the hooks P Q.

U is a tubular sleeve arranged over the 80 body and flange of the half-coupling, and adapted to be longitudinally movable thereon.

The sleeve U is provided with the vertical portion, which is cut away opposite the stud K. Interposed between the outer face of the 85 vertical portion of the flange B and inner face of the vertical portion of the sleeve U are the helical springs V. Four of such springs are shown in the drawings, Fig. 4, and serve the purpose of defining the position of the sleeve 90 relative to the end of the half-coupling and stud K, and by the compressibility of the springs allow the sleeve to be moved forward toward the point of junction of the half-coupling when acted upon by the hooked latches O. 95

The operation of my improved coupling is as follows: When it is desired to connect the half-coupling, the handles of the hooked latches are depressed and the faces D brought into apposition. The latches are then released, 100 when the hooks P Q will lap over and bear upon the end of the sleeves U. The depending por-

ions or tongues R of the latch O are thus brought in front of the studs K. Should the coupling be subjected to any unusual strain tending to draw it apart—as by the parting of 5 two cars of a train—the sleeves are moved by the latches toward the junction of the half-coupling. The movement of the latches brings the tongues R against the studs K, and by reason of the inclined face M the latches are 10 raised until the hooks P Q clear the face of the sleeves, when the coupling falls apart. The packing of the coupling at the junction of the half coupling is effected by means of the conical rings, which are advanced by the pressure 15 of the body transmitted through the coupling until the rings F are in contact, the practical effect being to produce an absolutely tight joint.

Fig. 1 shows the faces of the rings F in contact. The extent to which the rings F may be 20 advanced beyond the faces D of the half-couplings can be regulated by previously determining the width of the divisions I in the packing-rings F G.

I do not wish to limit myself to the precise construction shown in the drawings and described in the specification, as it will be obvious that 25 various modifications may be made in the device without departing from the intent of my invention.

30 I claim as my invention—

1. A two-part coupling, the parts of which are automatically detachable under strain and provided with axial port-openings, packing-

rings in said openings, latches pivoted to the body of the coupling, and longitudinally-mov- 35 able sleeves with which said latches engage, and studs under said sleeves, by reason of which said latches are disengaged, substantially as described.

2. In a two-part coupling, the combination, 40 with a loose sleeve on one part, of a stud under said sleeve and a hooked and tongued latch pivoted to the other part, substantially as described.

3. In a two-part coupling, the combination, 45 with a loose sleeve on one part, one end of which projects over said sleeve and stud, of a stud under said sleeve, a latch pivoted to the other part, and a spring under the handle of said latch, substantially as described.

4. In a two-part coupling, the combination, 50 with a loose sleeve on one part, of a spring under said sleeve, a stud under said sleeve, and a latch pivoted to the other part and engaging said sleeve, substantially as described.

5. In a half-coupling, the combination, with the body thereof, of a latch pivoted to one side of the body, a stud provided with inclined faces, and a loose sleeve provided with a slot 55 to allow passage of said stud, substantially as described.

GEO. H. BENJAMIN.
